United States Patent Office.

SELDEN W. KNOWLES, OF NEW HAVEN, CONNECTICUT.

Letters Patent No. 66,361, dated July 2, 1867.

IMPROVED CRADLE.

The Schedule referred to in these Letters Patent and making part of the same.

TO ALL WHOM IT MAY CONCERN:

Be it known that I, SELDEN W. KNOWLES, of New Haven, in the county of New Haven, and State of Connecticut, have invented a new Improvement in Child's Cradle; and I do hereby declare the following, when taken in connection with the accompanying drawings and the letters of reference marked thereon, to be a full, clear, and exact description of the same, and which said drawings constitute part of this specification, and represent, in—

Figure 1, a side view, and in

Figure 2 an end view, and by diagrams in red and blue illustrating its operation.

This invention relates to an improvement in cradle and crib combined, and consists in the peculiar manner by which the rocking motion is given to the cradle, and also, in combination therewith, an arrangement whereby the cradle may be held stationary and thus make a crib or cradle as desired.

To enable others to construct my improvement, I will proceed to a description of the same as illustrated in the accompanying drawings.

A is a frame or platform, supported upon casters B or otherwise, so as to form a firm bearing upon the floor. C the body of the cradle, of any convenient form or construction. At or near its two ends are attached the rocking-levers D and E, one end of each pivoted to the cradle at a, their other ends to the frame or platform A at d, crossing at the centre, as seen in fig. 2, but not so as to interfere with each other. When the cradle is rocked to the left as denoted in red, the lever D is depressed, while the lever E rises, as denoted in red, fig. 2. On its return to the other side, as denoted in blue, the other lever E is depressed in its turn and the lever D rises as denoted in blue. Thus continually rocking, the levers alternately rise and are depressed, giving to the cradle a longer and easier rock than is done by the common rocker, and dispensing with the long rockers, a recognized and admitted nuisance. To prevent the lateral movement of the cradle, as well as to prevent the lateral strain upon the levers, I arrange at a convenient point (preferring the centre,) a lateral guide, G, in which is arranged a friction-roll, f, attached by an arm, H, to the body of the cradle, which, as the body is rocked, moves up and down in the said guide, and prevents any lateral or endwise movement of the cradle. To hold the rockers and convert the cradle into a stationary crib, I arrange upon the frame A, and beneath the levers at one or both ends, a block, I, (see fig. 2,) which sets under the centre of the levers so as to prevent their movement, and holds the cradle stationary. This block is pivoted to the frame A, so as to be turned from its position under the levers to one side, as denoted in red, and when so turned permits the free movement of the cradle, and thus by simply turning the block I, the cradle may be changed to a stationary crib, or *vice versa*, as the case may be.

Having thus fully described my invention, what I claim as new and useful, and desire to secure by Letters Patent, is—

1. The arrangement of the levers D and E, pivoted to the cradle C and to the frame A, constructed and arranged so as to operate substantially in the manner herein set forth.
2. The arrangement of the guide G, in combination with the cradle C, so as to prevent the lateral movement of the cradle, and operate substantially as herein set forth.
3. The arrangement of the block I, in combination with the cradle C and levers D and E, so as to operate as and for the purpose specified.
